UNITED STATES PATENT OFFICE.

JAMES F. McELROY, OF ALBANY, NEW YORK; SUSIE H. McELROY, EXECUTRIX OF SAID JAMES F. McELROY, DECEASED, ASSIGNOR TO CONSOLIDATED CAR-HEATING COMPANY, A CORPORATION OF WEST VIRGINIA.

RAILWAY-SIGNAL.

1,186,923.

Specification of Letters Patent. Patented June 13, 1916.

Application filed March 23, 1912. Serial No. 685,808.

To all whom it may concern:

Be it known that I, JAMES F. McELROY, a citizen of the United States, residing at Albany, county of Albany, State of New York, have invented certain new and useful Improvements in Railway-Signals, the following being a full, clear, and exact disclosure of the one form of my invention which I at present deem preferable.

For a detailed description of the present form of my invention, reference may be had to the following specification and to the accompanying drawings, which illustrate my invention.

Figure 1 is a view of my trolley-wire circuit-closer and Figs. 2 to 8 inclusive show the details thereof and the corresponding circuit-breaker. Fig. 9 shows the circuit connections for a single track and Fig. 10 for a double track system.

My invention involves devices for enabling a traveling car or train to automatically give notice of its approach from any desired distance away, for instance, its approach to a crossing or station. It is particularly intended for an electric railway and the automatic circuit controllers which initiate and terminate the signal are arranged to be operated by the contact device or trolley traveling on the trolley conductor.

Referring to Fig. 1, an ordinary trolley wire is represented at 10, a trolley at 11 and a transverse span-wire support at 12. On span-wire 12 is suspended a cradle comprising the parallel insulating bars 21, which are immediately attached to the wire, and the transverse bars 22. The trolley-wire 10 is supported beneath one of the insulating bars 21, so that the cradle will hang at one side of said trolley-wire. On the aforesaid cradle is supported a switch box or casing 20 containing a switch, or circuit-controlling device acting in one case to close, and in the other case to open a branch circuit from the trolley-wire through a signal relay to ground. The switch is operated by a horizontal strike-bar which normally projects across and under the trolley-wire and stands in the path of trolley 11 so as to be struck thereby and turned in one direction or the other according to the direction in which the trolley is moving. Referring to Fig. 4 the said strike-bar is shown at 23

and is mounted on one end of a vertical spindle 30 which is journaled in a sleeve 31 that is formed integrally with the bottom-plate 24 of the box 20. The strike-bar thus comes below the box and also below the cradle so as to have free play. The spindle 30 carries on its inner end the radial contact arm 32, while there is interposed between the sleeve 31 and the spindle a coiled centralizing spring 38 which serves to bring the arm back to its normal position after the strike-bar 23 has been turned by the trolley in either direction. This spring arrangement is of a well known kind and the details thereof are shown in Figs. 4-8. The spring 38 is coiled on a spool 36 having loose flanges 36^a and 36^b that are connected respectively to the opposite ends of the spring. Each flange has also a radial lug marked 37^a and 37^b and, whichever way the contact arm or lever 32 is turned, the rear end or heel of the lever will engage and turn with it one of those lugs (together with the flange from which the lug projects and that end of the spring which is secured to that flange) while the other lug on the opposite flange, which is connected to the opposite end of the spring, will abut against a fixed stop on the stationary sleeve 31 and be held thereby. The spring will thus be put under tension by a movement of the contact-arm or lever 32 in either direction from its central position. The lug engaged by the arm when it is turned in—say a clockwise direction—will be the one to engage the fixed stop when the arm is turned in the anti-clockwise direction.

In the drawing the forward flange, 36^a, connected to the forward end of spring 38, has the radial lug 37^a, and the rear flange 36^b connected to the rear end of spring 38 has the radial lug 37^b. The fixed stop on sleeve 31 is shown at 35, and is overlapped by the lever-heel 33. In Fig. 7 the strike-bar 33 is in its normal central position, and lugs 37^a and 37^b both rest against stop 35 and also against the lever-heel 33. In Fig. 8 the strike-bar is turned to the left, turning with it the contact arm or lever 32. The lever heel 33 therefore moves to the right engaging and carrying with it the lug 37^a (secured to one end of spring 38) while the lug 37^b (secured to the opposite end of spring 38) engages the stop 35. Conversely,

when the strike-bar and contact-arm or lever 32 are turned to the right, as shown in Fig. 6, it is the lug 37^b which will be engaged by and carried with the lever-heel 33 and 5 the lug 37^a will abut against the stop 35 and be held thereby.

In the device of Fig. 2, which may be called the starting switch, since it is located at the distant point where the signal 10 action is initiated, the contact arm 32 will act to close a circuit whenever it is moved from its central position by a car approaching the crossing to be protected, or the station to be notified. On the contrary, the 15 contact arm will act to open a circuit in the device of Fig. 3, which may be called the crossing switch, since it is located at the crossing, or other place where the notice is to be received. Thus, in Fig. 2, if an approaching train, moving from right to left, as indicated by arrow 98, hits strike-bar 23 and thereby turns the contact arm 32 in a clockwise direction, the arm will engage contact spring 40 and close an electric circuit, (an oppositely moving train will also turn arm 32 in the opposite direction but will produce no effect thereby). But in 25 Fig. 3, the similar operation of arm 32 (in either direction) will merely remove it from its normal bearing on contact spring 41 and allow that spring to separate from the opposite contact spring 42 and thereby open the circuit which may at that time be closed by the contact of springs 41 and 42. A starting switch like that in Fig. 2 may be denoted by A and a crossing switch like that in Fig. 3 may be denoted by B.

Turning to Fig. 9 the circuit arrangement for a single track railway will there 40 be formed. In Fig. 9 a circuit-breaking crossing switch of the kind shown in Fig. 3 is indicated at B, this switch being installed near the crossing to be protected at a point where the ringing of the bell, which 45 has served as the signal, can safely be stopped. At a suitable distance along the railway on each side of the crossing or station at a point where the bell is to be started ringing by an approaching car or train I 50 install one of my circuit-closing starting switches of the kind shown in Fig. 2. The starting switch A will act, in the manner heretofore described to close momentarily a branch circuit 13 from the trolley wire 12 to ground. That will start the bell to ringing. The crossing switch B will act, in the manner heretofore described, to break a branch circuit 15 from the trolley wire 12 55 to ground. That will stop the ringing of the bell. The said branch circuit 13 comes to the signal apparatus and there passes, first, through a safety fuse 50, then through resistance 60, then through relay magnet 70 and goes thence to ground wire 14, which contains an electric signal bell 60

80 that may be of any form suitable for the current it receives. The closure of this branch circuit 13 by either of the starting switches A will energize relay magnet 70 and thereby close the aforesaid branch circuit 15 which comes from the crossing switch B to the relay contacts 72, 73 and passes thence through safety fuse 50, resistance 60, relay magnet 70 to ground wire 14 and bell 80. The said closure of this 75 circuit 15 requires only a momentary closing and excitation of circuit 13 by closing switch A, since the relay magnet 70, thereby energized, will be maintained energized by circuit 15 which it serves to close and 80 so will maintain the action of bell 80 until the approaching train reaches the crossing which the bell protects, and stops its ringing by breaking said circuit 15 at switch B. The relay magnet 70, being thus 85 deenergized, will open contacts 72, 73, so that although the break in circuit 15 at the switch B is only momentary and will be immediately closed as soon as the car or train passes switch B, yet the circuit 15 90 can not be reenergized until one of the starting switches A is again operated to reenergize the relay magnet by the momentary closure of circuit 13. When the car or train passes the crossing and becomes a 95 departing instead of an approaching car or train, it will of course encounter the other switch A, and its trolley will hit the strike-bar 23 thereof, but will turn it in the opposite direction which produces no 100 closure of the circuit 13. In other words each starting switch A is a "one-way" device that will be worked to close the circuit 13 by an approaching, but not by a 105 departing car or train.

Fig. 10 shows the circuit arrangements for a double track railway, wherein a car or train approaching from one direction uses one trolley wire and one approaching from the opposite direction uses a different and parallel trolley wire. In that case there will be a crossing switch B for each direction of approach and each switch B will have its individual starting switch A. I also prefer to provide a separate bell 80 with its separate 110 relay for each track, although a single bell and relay might be used by connecting the two starting switches thereto in multiple and the two crossing switches thereto in series. The single bell could therefore be started by either of the two starting switches and stopped by either of the two crossing switches.

The circuit 13 is not only a branch of the trolley conductor, but is also one of two 115 branches (circuit 15 being the other one) from the signal circuit which includes the bell 80, the relay 70 and the resistance 60. Moreover, the circuit 13, together with the signal circuit constitute a starting circuit 120 130

for the bell and the circuit 15 connected to said starting circuit at the point 16 constitutes a maintaining circuit therefor.

What I claim as new and desire to secure by Letters Patent is:

1. An improvement in railway signals comprising a signal element, a signal circuit including said signal element and a relay magnet, a circuit closer operated by said magnet, a branch circuit including said circuit closer, said magnet and said signal element, a normally open trolley operated switch for closing the signal circuit when moved in one direction only, means for moving said switch to break said signal circuit immediately after each circuit closing operation of said switch, a second trolley operated switch in the branch circuit, and means for maintaining the second switch in a normally closed position to keep the magnet energized after the signal circuit is broken by the first switch.
2. An improvement in railway signals comprising a signal element, a two-branched signal circuit including said signal element and a relay magnet, spaced-apart trolley-operated switches, one for each branch, for closing the signal circuit when moved in one direction only, each switch being operative when moved in a direction opposite the direction of operative movement of the other switch, each switch having means for automatically returning it to circuit breaking position after each operation, a branch cir-

cuit including said magnet, said signal element and a circuit closer operated by the magnet, a circuit breaking switch for said branch circuit, and means for holding said circuit breaking switch normally in circuit-closing position.

3. An improvement in railway signals comprising a signal element, a signal circuit including said element and a relay magnet, a circuit closer operated by said magnet, a branch circuit including said circuit closer, said magnet and said signal element, a trolley-operated switch provided with means for closing said signal circuit when moved in one direction, means for automatically returning said switch after each operation to a neutral position with the signal circuit normally broken, a second trolley-operated switch in the branch circuit provided with means for making and breaking said branch circuit, and means for automatically returning said second switch after each operation to circuit closing position with the branch circuit normally closed to keep the magnet energized after the signal circuit is broken by the first switch.

In witness whereof I have hereunto set my hand, before two subscribing witnesses, this 21st day of March, 1912.

JAMES F. McELROY.
